(57) **CLAIM**

The ornamental design for a closet with pegboard surface as shown and described.

DESCRIPTION

FIG. 1 is a front perspective view of a closet with pegboard surface showing the new design;

FIG. 2 is a left side view thereof, the right side view being a mirror thereof;

FIG. 3 is a front view;

FIG. 4 is a rear view;

FIG. 5 is a top view;

FIG. 6 is a bottom view;

FIG. 7 is a front perspective view configured with the doors open to show the interior thereof;

FIG. 8 left side view configured with the doors open, the right side view being a mirror thereof;

FIG. 9 is a front view configured with the doors open;

FIG. 10 is a rear view configured with the doors open;

FIG. 11 is a top view configured with the doors open; and,

FIG. 12 is a bottom view configured with the doors open. The surface shading is intended to depict surface contour and forms no part of the claimed design.

1 Claim, 12 Drawing Sheets
